UNITED STATES PATENT OFFICE.

PAUL PRIEM, OF HEIDENHEIM-ON-THE-BRENZ, GERMANY.

WOOD-GRINDER.

1,030,919.

Specification of Letters Patent.

Patented July 2, 1912.

Application filed July 15, 1909. Serial No. 507,840.

To all whom it may concern:

Be it known that I, PAUL PRIEM, a citizen of Germany, residing at Heidenheim-on-the-Brenz, Germany, have invented new and useful Improvements in Wood-Grinders, of which the following is a specification.

My invention relates to wood grinders and the primary object of my invention is to provide an efficient automatic feed for a fluid-operated reversible press.

In wood grinding machines with reversible presses as heretofore constructed, where any attempt has been made to secure an automatic feed of the wood to the press, the hopper containing the supply of wood has itself been made movable and has in fact constituted a portion of the press, which is directly subjected to the action of the pressure means. These hoppers from their very nature cannot hold a sufficient supply of wood to make the operation of the machine continuous and interruptions must occur at short intervals in order that the "presser hopper" may be recharged. Furthermore it is not possible to prevent the jamming of the wood in the hopper and consequently the feed is not automatic, but must be constantly maintained by an attendant who frequently loosens the jammed pieces so that they fall against the grinder. These delays materially diminish the capacity and therefore the value of the machine.

It is the object of my invention to provide means for automatically refilling the press from a stationary hopper, which may be of any desired size, so that the operation of the machine may be made substantially continuous and without interruption or stoppage for recharging with wood, or for dislodging jammed material.

In order that my invention may be clearly understood I will now explain the same with reference to the accompanying drawings in which several embodiments are represented diagrammatically by way of example.

In said drawings, Figure 1 is a vertical sectional elevation showing one form of wood grinder with sliding pressing-plates; Fig. 2 is a like view of a modified form, the pressing-plates being pivotally mounted so as to rock; Fig. 3 is a like view showing parts of another modified form of machine, several small presses of the type shown in Fig. 1 being provided, whereas Fig. 4 is a like view showing a modification of the

form illustrated in Fig. 2, Fig. 5 is a like view of part of a wood grinder, the pressing plate being replaced by an elastic steel belt; Fig. 6 is a vertical sectional elevation showing a further modification of the form illustrated in Fig. 2; and Fig. 7 is a like view showing parts of another modified form of the machine.

Referring to the drawings, in my new wood grinder the wood is pressed intermittently against the grindstone in well-known manner by mechanical or hydraulic pressure, etc., the one or more presses *e* of the machine being connected, however, in such manner to the one or more storage receptacles or hoppers that when a press recedes from the grind-stone it is automatically filled again. The movable part of the press or its driving gear is reversed automatically or by hand (preferably the former) when it is in definite position with relation to the grind-stone, for example in immediate proximity to the same, so that this movable part of the press returns to its initial position at an accelerated speed. This constant reciprocation of the presser proper at the base of the hopper keeps the sticks of wood in the lower portion of the latter in motion, without subjecting them to the pressure of the ram, and thus prevents jamming in the hopper. Upon the movement of the presser away from the grinder, therefore fresh wood automatically falls from the hopper *b* into the press, thus rendering superfluous the attendance at each press of workmen to reverse the empty presses and fill them again by hand. Consequently, since the operator only has to take care that a sufficient quantity of wood is in the large stationary hopper *b*, a single workman can attend to a relatively large number of grinders and at the same time preserve the same in uninterrupted operation. Furthermore, by reason of the fact that each press is again filled very rapidly and comes quickly into action again, the power employed is more uniform and is therefore more easily governed than when each press is out of operation for several minutes at short intervals as when they are filled by hand, as is now customary.

Referring now to Fig. 1, the wood is pressed against the grindstone *c* in well-known manner by longitudinally reciprocated pressing-plates *a'*, each being driven by the piston of a hydraulic cylinder *d*. By

means of a box b' shaped in its upper part like a roof and inserted in the hopper, in which box a sharpening roller e may be provided, the wood is distributed uniformly to the two presses. The plates g , g and g' , g' are made adjustable toward the grindstone by any suitable means and when the stone wears are adjusted correspondingly.

In the form represented in Fig. 2 the 10 pressing plates a' are pivoted to the bottom portion of the hopper b , which is filled with wood by a conveyer p for example. The wood is guided by the adjustable plates g , g which are shaped concentrically to the 15 centers of the pressing-plates a' . The rest of the machine is the same as in Fig. 1.

A modified form of the machine shown in Fig. 1 is represented in Fig. 3 where several small presses a are arranged around one 20 common grindstone c . These presses may have separated hoppers b or a common hopper. The guide plates g are made adjustable here also.

In Fig. 4 is illustrated a grinder with a 25 single large pivoted press of the kind shown in Fig. 2. The rocking pressing-plate a' reciprocated by means of the piston of a hydraulic cylinder d is pivoted below the grindstone c with its center on the lower 30 edge of the hopper b . In order to load the driving motor uniformly two such presses may be placed beside one another lengthwise of a single grindstone or bearing 35 against two narrow stones mounted on the same shaft, the two presses to be alternately reversed and filled.

In the form shown in Fig. 5 the pressing-plate is substituted by an elastic steel belt a^2 , one end of which is attached to the 40 adjustable plate g , the other end being guided over a roller or cylinder i arranged at the lower end of the hopper b and attached to a hydraulic cylinder d for which can be substituted a weight or the like. By tensioning or relaxing the steel belt the pressing-chamber is made smaller or larger, and when made larger fills automatically from the hopper b .

In the form shown in Fig. 6 the pressing 50 plate a' is pivoted to the base f of the machine instead of the bottom portion of the hopper b as in Fig. 2. The pressing plate a'' through the slotted middle part of which 55 enters an extension g''' of the adjustable plate g'' is driven by the piston of a hydraulic cylinder d . A similar press mechanism may be reversely arranged on the other side of the grindstone.

In the modified form of the machine 60 shown in Fig. 7 the pressing room a is formed within a vertical guide h which is open below and above and is adjustable toward the grindstone c . In this guide moves the vertically reciprocating pressing-box 65 a''' which embraces or is guided at its upper

end by the chute b forming the lower part of the hopper. The lower part of the pressing-box a''' diminishes in diameter from below to the top in order to receive inclined pressing-faces a'''' which are preferably 70 roughened for the purpose of securing a proper grip of the wood and pressing it effectually toward the grind-stone c . Several of the presses described may preferably be combined to one machine. The moving 75 of the pressing-boxes a''' may be effected in a suitable manner, for example by the piston of a hydraulic cylinder. When the pressing-box rises the wood advances automatically to the pressing-room so that also 80 in this case the feed of the material to the grind-stone can be looked upon as continuous during the entire operation of the machine.

Besides the constructional forms shown in 85 the drawings further forms can, of course, be made, all wood grinders whose pressing-chambers fill again automatically with wood after being emptied and the real pressing device being reversed or returned into its 90 commencing position automatically or by hand falling within the scope of the invention. The wood may be supplied continuously or periodically to the hopper.

I claim as my invention:

1. A wood pulp grinding machine comprising a grinding member, a presser member for forcing a charge of wood against the grinder, a reciprocating, fluid-operated motor operatively connected to said presser 100 member for imparting a positive back and forth motion thereto whereby the presser member may be advanced slowly under heavy pressure during grinding and rapidly retreated to receive a fresh charge, in combination with a superposed, stationary recharging hopper of sufficient size to hold a multiplicity of charges, said hopper opening to and automatically discharging by gravity to the space between the grinder 105 and the presser on the retreat of the latter and holding a quantity of wood sufficient to prevent the escape of the wood from the space between the grinder and the presser during the advance of the latter, substantially as described.

2. A wood pulp grinding machine comprising a grinding member, a presser member for forcing a charge of wood against the grinder, means for positively advancing and 110 retreating said presser, in combination with a superposed stationary hopper of sufficient size to hold a multiplicity of charges, the upper surface of said presser partially sustaining the reserve of wood in the hopper 115 above the same during its advance, and the acting face of the presser being formed to coöperate with the weight of the reserve of wood in the hopper to prevent the upward escape of the charge from the presser cham- 120 125 130

ber during the advance of the presser for grinding.

3. A wood pulp grinding machine comprising a grinding member, a presser member for forcing a charge of wood against the grinder, means for positively advancing and retreating said presser, in combination with a superposed stationary hopper of sufficient size to hold a multiplicity of charges, the upper surface of said presser partially sustaining the reserve of wood in the hopper above the same during its advance, but per-

mitting a succeeding charge to fall by gravity into the space between the presser and the grinder on the retreat of the presser, 15 substantially as described.

In testimony whereof I have signed my name to this specification, in the presence of two subscribing witnesses.

PAUL PRIEM.
